UNITED STATES PATENT OFFICE.

WILHELM VON NEUDECK, OF PHILADELPHIA, PENNSYLVANIA.

LATHING MAT.

Application filed December 1, 1924. Serial No. 753,039.

My invention relates to a novel lathing mat for use in the construction of plastered and cemented surfaces in building construction, such as walls and ceilings, arches and 5 columns, and it is particularly advantageous in the production of plastered and stuccoed walls and ceilings, since it is very easy of application and produces a very efficient binding surface for either plaster or cement.

10 My invention consists chiefly of a series of parallelly disposed narrow strips of wood, spaced apart, and of any suitable uniform length, secured to and carried by two or more parallel metallic strands such as flexible 15 wires, extending substantially at a right angle to the strips of wood, so as to form a mat composed of wooden strips and metallic retaining bands.

My invention further consists of a lathing 20 mat composed of parallel spaced strips of wood secured to transverse metallic bands by means of wires, which encircle the retaining band and each of the wooden strips, at the intersections of said wooden strips 25 and said retaining bands.

My invention further consists of a lathing mat as mentioned above, having however, a layer of paper secured to said strips of wood on the sides thereof opposed to the 30 metallic retaining bands, so as to form an efficient means of confining the plaster or cement during the application thereof, to substantially the thickness of the mat, thus preventing any wastage of the plastering or 35 cementing material due to the same being exuded between adjacent strips of wood.

For the purpose of illustrating my invention, I have shown in the accompanying drawings forms thereof which are at present preferred by me, since they will give in 40 practice satisfactory and reliable results, although it is to be understood that the various instrumentalities of which my invention consists can be variously arranged and 45 organized and that my invention is not limited to the precise arrangement and organization of these instrumentalities as herein shown and described.

Figure 1 represents a plan view of a plastered surface, partly broken away to expose 50 to view the novel lathing mat embodying my invention.

Figure 2 represents a section on line 2—2 55 of Figure 1, showing the construction of my novel lathing mat.

Figure 3 represents a similar section on

line 3—3 of Figure 1, showing my novel mat in place and the method of application of the same.

Figure 4 represents a section on an enlarged scale on line 2—2 of Figure 1 of a single lath strip and the manner of securing the same to the metallic retaining bands.

Figure 5 represents a section on line 5—5 of Figure 1, showing the manner in which 65 said lathing mat is secured to the studs.

Figure 6 represents a sectional view similar to Figure 2, showing a modified embodiment of my invention.

Figure 7 represents a sectional view similar to Figure 3, showing a modified embodiment of my invention and the application thereof.

Figure 8 represents a section of a portion of my novel matting applied to an arcuate 75 surface.

Similar numerals of reference indicate corresponding parts in the figures.

Referring to the drawings, 1 designates the lath strips composed of any suitable 80 wood, and of substantially rectangular cross section, disposed parallelly and spaced apart equal distances substantially of the width of a strip. The strips 1 are all of substantially the same length, which may be any 85 suitable length as required for the particular work, although the length most commonly used is one yard. The strips 1 are carried by and secured to, two or more heavy flexible wires 2 in a continuous manner, so as 90 to produce a mat, of a width equal to the length of the strips, and of any length that may be desired. Due to the flexibility of the retaining wires, the mat may be flexed 95 transversely of the length thereof, thus permitting said mat to be rolled up into a compact roll which is easily handled and transported.

Each of said lath strips 1 is secured to each of the retaining wires 2 at the intersections thereof, by means of the thin securing wires 3, which are wrapped around said retaining wires 2 firmly, and then closely encircle the particular lath strip, and are then again wrapped around the retaining wire, thus securing the strips 1 to the retaining wires 2, both against transverse and longitudinal displacement.

The novel lathing mat thus produced, may then be applied to the studs 4, or other cross 110 members of walls, ceilings or columns, by simply placing said mat thereon with the re-

taining wires on the outer side, and securing the retaining wires at intervals, by nails or staples 5, as shown in Figure 5.

In order to prevent the plaster material 6 from falling through, or being exuded through the spaces between the lath, there is provided on the inner side of said mat, namely the side opposed to the retaining wires, a layer of fibrous material such as the 10 paper 7, which is secured to said strips of wood by means of any suitable adhesive, as shown in Figures 2, 3, 6 and 7.

In order to prevent any longitudinal slipping of the individual lath strips with respect to the mat, the securing wire 3, as shown in Figure 4 on an enlarged scale, is wound around the retaining wire 2 sufficiently tight to cut into the lath strip a substantial distance, thereby fixing the said lath 20 strip to said retaining wire, relative to any longitudinal movement thereof.

In order to produce a more effective binding of the plastering material, than would be obtained on the matting composed of rectangular strips as shown in Figures 1 to 4 inclusive, I may construct my novel lathing mat of wooden lath strips having non-parallel inclined sides such as those of a trapezoidal cross section shown in Figures 6 and 7.

30 In this modification of my novel lathing mat the lath strips 8 are secured in a similar manner to the retaining wires 2, with the longer of the parallel sides of said trapezoidal cross section adjacent to the retaining wires, so as to produce, when assembled, grooves between the adjacent lath strips, which will have inwardly inclined walls. By this modified form of my novel construction there is obtained a positive locking of 40 the plaster in the inwardly enlarged grooves produced by the adjacent lath strips.

My novel lathing mat is adaptable to vertical as well as horizontal surfaces and also to curved or arcuate surfaces of any degree 45 of curvature, in which latter case, as shown in Figure 8, the matting is simply bent around the curve with the lath strips extending parallel to an element of the curved surface. In Figure 8, there is shown such an 50 application of my novel lathing mat, which figure represents a horizontal section of a portion of the outer surface of a column, the lath strips extending vertically.

By my novel construction in lathing there 55 is produced an effective and inexpensive method of plastering which at the same time

produces a very durable surface. The lathing mat being composed of inexpensive materials and being readily produced, may itself be marketed at a very low cost compared 60 with most other lathing materials heretofore known.

Due to the fact that the strips of my novel lathing are not secured to the studs individually, but the matting in itself is secured 65 by means of the retaining wires 2 and the staples 5 at suitable intervals, said matting may be readily applied to any wall or ceiling structure with a saving of time and also 70 without the aid of skilled help, thus reducing the cost two fold.

The staples 5 may be applied with great 75 rapidity and without the aid of skilled help by the use of nailing guns designed for that purpose.

In addition to the reduction of cost, in the initial cost of the lathing and in the cost of its application to the building structure, the lathing of my novel construction produces a 80 more effective plastering foundation, and hence a more durable plastered surface, than that produced by lathing material known heretofore.

It will now be apparent that I have devised a novel and useful lathing mat, which 85 embodies the features of advantage enumerated as desirable in the statement of the invention and the above description, and while I have, in the present instance, shown and described a preferred embodiment thereof 90 which will give in practice satisfactory and reliable results, it is to be understood that such embodiment is susceptible of modification in various particulars without departing from the spirit or scope of the invention 95 or sacrificing any of its advantages.

Having thus described my invention, what I claim as new and desire to secure by Letters Patent, is:—

A lathing mat consisting of a plurality of 100 substantially parallel strips of wood having front and rear faces, a plurality of relatively thick and rigid retaining wires extending transversely of said series of parallel strips of wood along their front faces, a relatively 105 thin securing wire encircling alternatively a retaining wire and a wooden strip and a sheet of paper adhesively secured to the rear faces of said wooden strips, opposed to said retaining wires.

WILHELM VON NEUDECK.
